UNITED STATES PATENT OFFICE.

WALTER S. ANDERSON AND ERNEST L. WATERHOUSE, OF DETROIT, MICHIGAN,
ASSIGNORS TO EARL HOLLEY, OF DETROIT, MICHIGAN.

APPARATUS FOR MAKING METAL MOLDS.

Application filed September 26, 1923. Serial No. 664,806.

To all whom it may concern:

Be it known that we, WALTER S. ANDERSON and ERNEST L. WATERHOUSE, citizens of the United States, residing at 1602 Parkview Ave. and 1163 E. Euclid Ave., Detroit, in the county of Wayne and State of Michigan, have invented certain new and useful Improvements in Apparatus for Making Metal Molds, of which the following is a specification.

This invention relates to the art of manufacturing iron castings in permanent molds and its object is to facilitate the manufacture of metal molds generally and specifically of hollow cast iron molds which are made in halves (so as to form two-part molds) from permanent master metal molds. Such molds have been successfully used in the manufacture of cast iron carburetors and automobile engine pistons, but the means shown are obviously adapted for making molds for other purposes.

These molds are preferably painted with a coating corresponding to that described in the United States patent to Meloche, U. S. #1,453,593. In order to get this coating to adhere to the metal surface the iron mold itself should be solid and free from blow holes and should generally be a sound casting and conform closely to the contour of the master mold. As is well known, the iron that is cast in an iron mold is denser and is particularly free from blow holes. It has therefore been found highly desirable to cast the permanent molds themselves in permanent molds.

The molds cast are of the general type described by Phillips, U. S. Patent #1,099,997. That is to say, a rib or beading is left around the mold for the purpose of conveniently matching the two halves together and giving sharp edges to the mold cavities as described in the Phillips patent.

The outline indicated on the drawings illustrates a mold adapted for use in the production of an automobile carburetor mold.

Figure 1 shows a cross sectional elevation of the master mold and core in the vertical position after pouring with the matrix of the mold full of iron.

Figure 2 shows the core in elevation.

Figure 3 shows in elevation the corresponding mold.

Figure 4 shows the mold and core assem-

bled and clamped together in the horizontal position.

In Figure 1, A is the dry sand sprue, B is a perforated strainer gate containing five $\frac{1}{4}$ " holes, C is the mold proper consisting of a gray iron casting, D is the central projecting portion which corresponds to the contour of a carburetor casting, E is a dry sand core the elevation of which is shown in Figure 2.

F is a perforated iron plate which is clamped onto the mold C by C-clamps, one of which is shown in Figure 4. G are the dowels which locate the core E onto the mold C. They consist of $\frac{3}{4}$ " pins projecting from the mold C. H H are the four ejection pins for ejecting the mold, J is a casting bolted to the mold C and supporting the ejection mechanism, K is a threaded rod which is free to rotate between the casting J and the mold C, L is a plate to which the ejection pins H are bolted and to which the rod K is threaded, M is the handle fitted to a squared portion on the end of the threaded rod K for operating the ejection device.

In Figure 2, the lateral gates Y Y and the vent Z are provided so that the iron as it is poured into the molds is distributed equally, flows uniformly and is vented thoroughly through the vent Z, this being a passage left in the core E for this purpose. The rectangular gate Y is arranged so as to be easily broken off, the edge of the gate Y being cast next to the edge of the mold O.

In Figure 3, N is the sprue below the gate B, P is the gate of the negative mold which of course is a convex surface in the positive master mold. Q and R are the core prints for the negative mold. The master mold C is pivotally mounted on trunions U V in a stand S (Fig. 4) and the handle T (Fig. 1) is provided for conveniently swinging the mold into the horizontal, vertical and inverted position for setting the core, pouring and ejecting the casting respectively.

In Figure 4, the mold is shown in the assembling position. The cap screws W W are provided for the trunions U V so that the mold may be locked in any position. A C-clamp X is shown holding the core E and plate F in place so that there will be no danger of displacing the core during the pouring operation. Actually three C-clamps are required.

Operation.—The mold C is mounted on the trunnions U V and casting S. The whole mold C, being free to rotate, is placed in the horizontal position and locked by the 5 cap screws W as shown in Figure 4.

The mold surfaces of C are cleaned and painted with the coating described in the Meloche patent referred to above and finally covered with a coating of freshly deposited 10 lampblack and the mold is then heated to 500° or 600° F.

The core E is coated with Cooper's core paste mixed with blue clay and graphite, the core being a dry sand core which has been 15 thoroughly baked so that there is no moisture present anywhere during the casting operation.

The ejection pins H are withdrawn so as to be flush with the mold C. The dry sand 20 core E is then placed on the mold C, being placed carefully in position and located by the dowel pins G. The perforated plate F is then placed upon the core E and three 25 C-clamps (only one shown, Fig. 4) are then used to clamp the plate F to the mold C. These clamps are left in place until the cast mold has solidified.

The mold is then rotated 90° so as to be vertical and the dry sand sprue and gate 30 A—B is placed opposite the gate N, as shown in Figure 1. The iron is poured in through A—B N Y and it flows into O, flowing uniformly over the mold D which is heated thereby. After the casting has solidified 35 the C-clamps are removed. The mold is then rotated another 90° so as to bring the mold in the inverted position with the ejection device H, J, K, L, M upwards.

Finally by rotating the handle M the 40 threaded rod K is caused to move the plate L out and carry with it the four ejection pins H thereby ejecting the negative mold O from the positive master mold C D.

By pouring the mold vertically a greater 45 head is available for ensuring complete filling of the mold and there is less danger of the molten iron prematurely congealing and so spoiling the perfect reproduction of the contours of the master mold desired.

50 By using a dry sand core the iron flows to the mold freely without being premature-

ly chilled, because although the mold C is heated it still is much lower in temperature than the molten iron. Further, the core is porous and to a certain degree vents the 55 mold.

Obviously the means shown above are adapted for casting solid molds, in which case the use of a dry sand core projecting into the box C will not be needed.

What we claim is:

1. Means for manufacturing hollow cast iron molds from a permanent metal master comprising an open box, a metal master mounted therein, a dry sand core adapted to project into said box and to provide a lateral gate, means for pivotally supporting said mold whereby the core may be located and clamped in place in the horizontal position, the lateral gate rotated into the vertical plane, the mold poured in the vertical position through the vertical gate, and the cast mold ejected from the said box in the inverted position.

2. Means for manufacturing hollow cast iron molds from a permanent metal master comprising an open box, a metal master mounted therein, a dry sand core adapted to project into said box and to provide a lateral gate, ejection means associated with said box, means for pivotally supporting said mold whereby the core may be located and clamped in place in the horizontal position, the lateral gate rotated into the vertical plane, the mold poured in the vertical position through the vertical gate, and the cast mold ejected from the said box in the inverted position.

3. Means for manufacturing cast iron molds from a permanent metal master, comprising an open box, a metal master therein, means for pivotally supporting said box, gating means for pouring molten metal endways into said box after the box has been rotated so as to bring the metal master into the vertical plane, ejection means associated with said box.

In testimony whereof we affix our signatures.

WALTER S. ANDERSON.
ERNEST L. WATERHOUSE.
